(57) **CLAIM**

The ornamental design for a portable device for creating mist, as shown and described.

DESCRIPTION

FIG. 1 is a top, front perspective view of a portable device for creating mist embodying my new design;

FIG. 2 is a front view thereof;

FIG. 3 is a rear view thereof;

FIG. 4 is a side view thereof as seen from the right-hand side of FIG. 2;

FIG. 5 is a side view thereof as seen from the left-hand side of FIG. 2;

FIG. 6 is a top view thereof;

FIG. 7 is a bottom view thereof; and,

FIG. 8 is a top, front perspective view thereof, the device being shown with a capsule and a cap removed from the device.

Portions of the portable device for creating mist shown in phantom lines in FIGS. 1-7 form no part of the claimed design.
